Inventor

T. J. Burke

United States Patent Office.

T. J. BURKE, OF CHICAGO, ILLINOIS.

Letters Patent No. 73,576, dated January 21, 1868.

IMPROVED CONCRETE-BRICK PRESS.

The Schedule referred to in these Letters Patent and making part of the same.

TO ALL WHOM IT MAY CONCERN:

Be it known that I, T. J. BURKE, of Chicago, in the county of Cook, in the State of Illinois, have invented a useful Improvement in Concrete-Brick Presses; and I do hereby declare that the following is a full and exact description thereof, reference being had to the accompanying drawings, and to the letters of reference marked thereon, making a part of this specification, in which—

Figure 1 is a sectional elevation of my invention.

Figure 2, a top view of the same.

My invention relates to that class of machines which are designed to make concrete blocks or bricks, of the required size, by hand-power; and its nature, in part, consists in the use of a substantial frame, inside of which is arranged a pressing-box, cam-wheel, rack-standard, ratchet-lever, and such other mechanical appliances as will make brick more readily, and in a more convenient manner than other hand-machines now in use for a similar purpose.

In order to give a correct understanding of my invention, I have marked corresponding parts with similar letters, and will now give a detailed description.

A, fig. 1, represents one side, and A A, fig. 2, both sides of the iron frame used in connection with my device. The sides are made to rest on an iron bottom, Z, fig. 1, and are bolted together at E E E E, two flanges, W, being used to hold the bottom in position and the ends of the pressing-box their tops. These ends are shown at B B in both figures, and are fitted closely against sides A A, so as to form a pressing-box, open at its bottom, and to be covered by a lid, I, jointed to frame A A at F. This lid can be thrown open, as seen at fig. 2, for receiving concrete, and shut, as seen at fig. 1, when a block is to be pressed; a lever-catch, H, jointed to frame A A, being used to hold said lid in place.

The pressing-apparatus is constructed as follows: A cam-wheel, R, has bearings passing through the frame A, and is arranged to be turned in either direction by means of a lever, U J, fitted to work on the ends of said bearings, as seen at fig. 2; and a lever, K, fig. 1, is made with a circular bearing at its bottom to fit the cam-wheel R, and extend up to the under side of the plunger D, at the bottom of the pressing-box, for the purpose of forcing said plunger upward and compressing the concrete therein. This plunger D has two slides, Y, attached to it, (one on each side,) and arranged to run in guides, X, secured to both of the inner sides of the frame A A, as seen at fig. 1, for the purpose of keeping its upper surface parallel with the under side of the lid I. One or more racks, L, as seen by dotted lines, are made in the slides Y, and arranged to mesh in a ratchet, M, rigidly attached to a lever, N S, having a fulcrum-pin, P, put through frame A A, in order that said lever may be used to force brick out of the box B B after the same has been compressed.

I use any suitable material for making my press, such as iron, steel, and wood, as the case may require. I, however, prefer iron, as being the cheapest for hand-presses, and fully answering the purpose.

Operation.

In order to put the press in position for use, the lever J should be raised up in a vertical position, as seen at fig. 1, after which the lid I should be thrown open, as seen at fig. 2; after which the box B B can be filled with concrete, and closed by the lid I, and secured by the lock H, as seen at fig. 1. This being done, the lever J should be brought to a horizontal position, as at fig. 2, which will compress the concrete in the box. The brick can be thrown out of the box B B after the lid I is raised, by forcing the lever N S downward to such a point as will raise the follower D to the top of the box.

Having thus described my device, what I claim, and desire to secure by Letters Patent, is—

The cam-wheel R, in combination with lever J, follower D, slides X X, lever N S, and box B B, arranged to operate in the manner as herein set forth.

T. J. BURKE.
